UNITED STATES PATENT OFFICE

150,417

DESIGN FOR A ROLL TISSUE HOLDER

Russel E. James, Guthrie, Okla.

Application November 25, 1946, Serial No. 135,056

Term of patent 14 years

(Cl. D4—3)

To all whom it may concern:

Be it known that I, Russel E. James, a citizen of the United States, residing at Guthrie, in the county of Logan and State of Oklahoma, have invented a new, original, and ornamental Design for a Roll Tissue Holder, of which the following is a specification, reference being had to the accompanying drawing, forming part thereof.

The figure is a perspective view of a roll tissue holder, showing my new design.

I claim:

The ornamental design for a roll tissue holder, as shown.

RUSSEL E. JAMES.
